UNITED STATES PATENT OFFICE.

UTLEY WEDGE, OF ARDMORE, PENNSYLVANIA.

TREATING LEAD MATTE.

1,198,882.

Specification of Letters Patent. Patented Sept. 19, 1916.

Application filed January 29, 1913. Serial No. 744,894.

To all whom it may concern:

Be it known that I, UTLEY WEDGE, a citizen of the United States, residing in Ardmore, Pennsylvania, have invented certain 5 Improvements in Treating Lead Mattes, of which the following is a specification.

My invention relates to the roasting of lead sulfid, lead ores, lead concentrates, lead matte, or other lead compounds (hereinafter 10 referred to as "lead matte") in furnaces of the superposed hearth type, the object of my invention being to provide for the driving off of the sulfur without causing the fusing or sintering of the matte or rendering it sticky so as to interfere with the 15 mechanical operation of the furnace.

Prior to my invention many attempts have been made to roast lead matte in furnaces of the superposed hearth type having mechanical rabbles, such for instance as shown in 20 United States Patents Numbers 556,750, dated March 24, 1896; 629,023, dated July 18, 1899; 648,183, dated April 24, 1900; 673,174, dated April 30, 1901; 700,339, dated 25 May 20, 1902, and others. Such attempts have not met with success, because, in a furnace of the superposed hearth type, in which the air for oxidizing the calcine is admitted at the lower portion of the furnace 30 and the draft is upward to an outlet or outlets located in the uppermost treating chamber, the gases accumulate heat as they pass in succession over the superposed hearths, the consequence being that, in the upper 35 chambers of the furnace, so high a temperature is reached that the incoming supply of lead matte soon becomes sticky so that it cannot be stirred or moved over the hearth by the rabbles.

40 It has hitherto been possible to roast lead matte in single hearth furnaces because, in a single hearth furnace, there is no progressive concentration of heat such as occurs in a multiple hearth furnace, but on account of 45 the high fuel cost of roasting lead matte in a single hearth furnace, either rabbled by hand or mechanically operated, it has been desirable for many years past to accomplish the roasting of lead matte in a multiple 50 hearth furnace.

In order to meet the difficulty encountered in roasting lead matte in a furnace of the superposed hearth type I made extensive investigations and found that lead matte containing 55 a considerable percentage of sulfur (as, for example, twenty per-cent.) became

sticky when heated to a temperature of 1400° F., (a temperature much less than that of the upper portion of a superposed hearth furnace operated in the ordinary way) but 60 that, as the roasting progressed and the sulfur content of the calcine became less, the temperature to which the lead matte could be subjected without becoming sticky rose steadily, until, with a sulfur content of thirteen per-cent., the calcine could be subjected to a temperature several hundred degrees in excess of 1400° F., without encountering the 65 difficulty.

In carrying out my invention, therefore, 70 I maintain a lower temperature in the upper portion of the furnace than in the lower portion of the same, preferably by abstracting heat from the gases rising from the lower into the upper chambers of the furnace, my purpose being to pass the lead matte downwardly from chamber to chamber of the furnace in the ordinary way and to maintain in the different chambers of the 75 furnace temperatures sufficient to effect the 80 desired sulfur elimination but not high enough to effect sintering or cause the lead matte to become sticky.

The control of the temperature in the upper portion of the furnace, for example, in the first four chambers at the top of a seven hearth furnace, may be effected by different means, as for example, by hearths equipped with a cooling medium such as internal air ducts or passages as in my Letters Patent 85 No. 946,178, dated January 11, 1910, whereby the temperature of a chamber may be lowered or raised at will by increasing or decreasing the supply of air to the ducts, or 90 rabbles arms can be provided of such dimensions as to permit of the absorption of surplus heat by cooling fluid circulated within the rabbles arms, as in my Letters Patent No. 916,234, dated March 23, 1909 the abstraction of heat from the chamber being 95 controlled by the greater or less supply of cooling fluid to the arms in that chamber, or the gases from the lower portion of the furnace can be passed through a cooler before being admitted to the chamber or chambers above, or, in a muffle furnace, heat can 100 be applied to the hearths wherein heat is necessary to secure the required elimination of sulfur and the chambers in which the temperature might become too high may be 105 opened to the atmosphere to a greater or less extent, but to secure the advantages and 110

the economy of direct fire I prefer direct application of heat in the lower portion of the furnace where a high temperature is necessary to carry the elimination of sulfur from the calcine to the desired point, and then, instead of allowing all of the hot gases to pass through the chambers above in series, I prefer to permit of the escape from such chambers, of such portion of the heated 10 gases as may be necessary to avoid excessive temperatures therein, such escape being effected preferably from several regulable outlets in each of such chambers so that the higher fuel economy may be attained by 15 using all of the heat that can safely be used in the lower portion of the furnace, applying the same to the upper treating chambers of the furnace but abstracting such portion of the same as may be necessary to avoid 20 reaching the sticky or sintering temperature in any chamber of the furnace.

In the accompanying drawings I have illustrated so much of a furnace of this type as is necessary for a proper understanding 25 of my present invention, Figure 1 representing a vertical section of the furnace, and

Fig. 2 a transverse section on the line $\alpha-\alpha$, Fig. 1.

This furnace has seven treating chambers numbered from top to bottom 1, 2, 3, 4, 5, 6 30 and 7, the chambers 1, 2, 3, and 4 being provided with dampered outlets 1^a, 2^a, 3^a and 4^a whereby the escape of the heated gases therefrom may be regulated.

I claim:

The mode herein described of roasting lead matte in a furnace of the superposed hearth type, said mode consisting in carrying said lead matte forwardly through the furnace, retarding sulfur elimination by abstracting heat from the furnace until the sulfur has been so far reduced as to permit of the free application of the heat necessary to effect the desired desulfurization, and then applying such higher heat. 40 45

In testimony whereof, I have signed my name to this specification, in the presence of two subscribing witnesses.

UTLEY WEDGE.
